PORTABLE GOLF TEE SUPPORT

Homer D. Hendricks, Seattle, Wash.

Application May 2, 1947, Serial No. 745,607

3 Claims. (Cl. 273—33)

1

This invention relates to improvement in portable golf tee supports and more particularly to a device for resiliently supporting a golf tee and providing directional indicating means to assist a golfer in aligning the swing of his club with the proper direction of the drive and in properly aligning the club face with a tee-supported ball.

It is among the objects of the present invention to provide an improved golf-tee support which will resiliently support a golf tee at any desired height so that a ball may rest on the tee in proper position to be driven, which provides directional indicating means for aligning the direction of the swing of the golf club and for properly aligning the face of the club with the ball, which will protect the head of the club against contact with the ground in the event the swing of the club is not properly made, which is of sufficient area to underlie the club head as it approaches the ball during a driving swing, is of sufficient weight to resist displacement even if contacted by the head of the club, is light in weight and can be easily carried, is neat and attractive in appearance, and is economical to manufacture.

Other objects and advantages will become apparent from a consideration of the following description in conjunction with the accompanying drawings wherein:

Figure 1 is a top plan view of an improved golf driving aid and tee support illustrative of the invention.

Figure 2 is a longitudinal sectional view on the line 2—2 of Figure 1.

Figure 3 is a transverse sectional view on the line 3—3 of Figure 2; and

Figure 4 is a bottom plan view of a fragmentary portion of the device.

With continued reference to the drawings the improved driving aid and tee support comprises a flat, elongated, substantially rectangular pad or mat preferably formed of flexible or resilient material such as rubber or synthetic rubber having a smooth upper surface provided with a finish adapted to offer minimum frictional resistance to a club head coming in contact therewith. This pad has a V-shaped notch 11 in one end portion thereof preferably so disposed that the longitudinal center-line of the pad passes through the apex of the notch. A bore 12 extends from the apex of notch 11 through the pad to an elongated aperture or recess 13 which is disposed intermediate the length of the pad and opens to the bottom surface thereof. A second bore 14 opens to the end of the pad opposite to

2

the end in which the notch 11 is provided and is so disposed that its center-line is substantially coincident to the longitudinal center-line of the pad. The inner-end of this bore is spaced from the inner-end of the bore 12, as is clearly shown in Figure 2. A twisted strand 15 extends through the bore 14 and is provided at one end with a loop through which passes a rivet 16 securing the strand in the bore and at its opposite end with a loop through which passes a carrying ring 17 by means of which the pad may be carried by hand or may be attached to a suitable clip worn on the person of the user.

15 A flexible strand 18 made of rubber or some resilient material, extends through the bore 12 and has one end provided with a loop in which is received a portion of a flattened ring 19 receivable in the elongated aperture 13. A loop at the opposite end of strand 18 receives a ring 20 which surrounds the reduced intermediate portion of a tubular golf tee support 21 dimensioned to receive the shank portion of a golf tee 22. The holder 21 receives the shank of the tee with sufficient friction so that the tee can be supported at 20 any desired height in the holder.

25 A golf ball 23 is supported on the tee 22 in position to be driven from the tee by a golf club and the flexible strand 18 permits the tee holder 21 to move so that the tee and the holder may move with the ball away from the pad at the time the ball is struck. The flexible strand will automatically return the tee and holder to the normal operative position at the apex of the V-shaped notch 11.

30 In case the strand 18 should be broken and it should become necessary to replace the tee holder, the end of the strand at the tee holder may be released and the strand withdrawn through the bore by pulling the flat ring 19 out of the aperture 13. A new strand may then be reinserted in the bore and when the ring 19 is seated in the aperture 13 it will hold the inner-end of the strand in proper position.

35 The face of the pad is provided with a directional indicator marking generally indicated at 24. This marking may conveniently comprise an elongated rectangle 25 extending from the ring-attached end of the pad, which is the left-hand end as viewed in Figure 1, to the base of an isosceles triangle 26 the apex of which is located adjacent to the apex of the notch 11. The rectangle 25 and triangle 26 together constitute an arrow-shaped marking the center-line of which lies along the center-line of the pad and the point of which is adjacent to the apex of the

notch and points directly at the tee 22 held at the apex of the notch. A directional line 27 is provided along the center of the rectangle 25 and terminates near the apex of the triangle 26 to provide an accurate directional indicator for aligning the swing of a golf club in the proper direction for the drive, the arrow itself, indicating the general direction of the swing and also assisting the golfer in lining up the swing of his club with the direction between the golf tee and the hole constituting the target of the drive. A plurality of spaced parallel lines 28 extend across the triangular portion 26 of the arrow, and the adjacent portion of the rectangular portion 25 to aid in properly aligning the face of a golf club with a ball carried on the tee 22.

The directional-indicator marking may be provided by applying pigment to the surface of the pad or mat or by using inlays of differently colored materials or in any other convenient or desired manner.

In using the device the pad or mat is placed upon the driving tee and arranged so that the arrow points directly in the direction in which it is intended to drive the ball. The golfer may then take a stance beside the mat and adjust his swing until it follows the line of the directional arrow and adjust his grip until the club face is perpendicular to the ball at the point of contact of the club head with the ball. This will greatly assist the average driver in obtaining a drive of accurate direction and satisfactory distance. The pad also protects the club head from coming into contact with the surface of the tee where it may be damaged by small stones and other hard material and prevents loss or breakage of the golf-ball supporting tee.

The invention may be embodied in other specific forms without departing from the spirit or essential characteristics thereof. The present embodiments are, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

What is claimed is:

1. A golf tee support, comprising a flexible

pad provided at one end with an open notch, said pad having an elongated bore extending to the closed end of the notch, a longitudinally elastic element mounted within the bore, a ring secured to the free end of the elastic element, a tubular holder provided between its ends with a reduced portion for receiving the ring thereon, the tubular holder being substantially vertically arranged within the notch and engaging the pad above and below the bore, and a tee having a shank inserted within the tubular holder.

2. A golf tee support, comprising a flexible pad provided at one end with an open notch, said pad having an elongated bore extending at one end to the open notch and having an opening leading into the opposite end of the bore and passing through one face of the pad, the opening extending laterally beyond the bore, a longitudinally elastic element mounted within the bore, a tubular holder for arrangement within the notch and connected with the elastic element, a retaining element arranged within the opening and secured to the elastic element and projecting laterally beyond the bore, the retaining element being removable from the opening, and a tee having a shank for insertion within the tubular holder.

3. A golf tee support, comprising a pad having an open notch, a longitudinally elastic element leading to the notch and secured to the pad, a substantially vertical tubular holder secured to the elastic element and arranged within the notch to be held in place by the elastic element, and a tee having a shank for insertion within the tubular holder, the shank having frictional engagement within the tubular holder so that the tee may be adjusted to different elevations and held in the selected adjusted position.
